The ornamental design for a single bag with a black inner portion and a white outer portion with pattern, as shown and described.

DESCRIPTION

FIG. 1 is a front view of a single bag that includes a white outer portion with pattern, the back view being the same as the front view;

FIG. 2 is an inside-out front view of the single bag of FIG. 1 showing the black inner portion of the single bag, the inside-out back view being the same as the inside-out front view;

FIG. 3 is a close-up view of the broke line box 3 of FIG. 1; FIG. 4 is a close-up view of the broke line box 4 of FIG. 2; FIG. 5 is a cross-sectional view taken along line 5-5 of the portion shown in FIG. 3;

FIG. 6 is a cross-sectional view taken along line 6-6 of the portion shown in FIG. 4;

FIG. 7 discloses the outer bag portion shown in FIG. 3 in a stretched configuration;

FIG. 8 discloses the outer bag portion shown in FIG. 4 in a stretched configuration;

FIG. 9 is a front view of an alternative embodiment of a single bag that includes a white outer portion with pattern, where the single bag includes a skirt of no specific length; FIG. 10 is an inside-out front view of the single bag of FIG. 9 showing the black inner portion of the single bag, where the single bag includes a skirt of no specific length, and the inside-out back view being the same as the inside-out front view;

FIG. 11 is a close-up view of the broke line box 11 of FIG. 9;

FIG. 12 is a close-up view of the broke line box 12 of FIG. 10;

FIG. 13 is a cross-sectional view taken along line 13-13 of the portion shown in FIG. 11;

FIG. 14 is a cross-sectional view taken along line 14-14 of the portion shown in FIG. 12;

(Continued)

FIG. 15 discloses the outer bag portion shown in FIG. 11 in a stretched configuration; and, FIG. 16 discloses the outer bag portion shown in FIG. 12 in a stretched configuration.

The broken lines in the drawings illustrate portions of the single bag that form no part of the claimed design. Where a broke line box is indicated, material inside the box is part of the claimed design. The broken lines showing broken away portions illustrate the bag has no specific length.
